US0D1106384S

(12) **United States Design Patent** (10) **Patent No.:** **US D1,106,384 S**
(45) **Date of Patent:** **** Dec. 16, 2025**

(54) **CONNECTOR FOR A TANK STAND**

(71) Applicant: **AMTROL LICENSING INC.**, West Warwick, RI (US)

(72) Inventors: **Christopher Kampf**, Chepachet, RI (US); **Jeffrey Neto**, Cumberland, RI (US); **Ken Cerpovicz**, Warwick, RI (US); **Jody McKinley**, Mt. Vernon, OH (US)

(73) Assignee: **AMTROL LICENSING INC.**, West Warwick, RI (US)

(**) Term: **15 Years**

(21) Appl. No.: **29/861,942**

(22) Filed: **Dec. 5, 2022**

Related U.S. Application Data

(63) Continuation of application No. 29/715,004, filed on Nov. 27, 2019, now Pat. No. Des. 975,821.

(57) **CLAIM**

The ornamental design for a connector for a tank stand, as shown and described.

DESCRIPTION

FIG. 1 is a perspective view of a connector for a tank stand; FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The evenly spaced broken lines depict portions of the connector for a tank stand that form no part of the claimed design.

1 Claim, 4 Drawing Sheets
